UNITED STATES PATENT OFFICE

96,811

DESIGN FOR A PIANO

Clarence F. Brey, New York, N. Y.

Application July 20, 1935, Serial No. 57,760

Term of patent 14 years

To all whom it may concern:

Be it known that I, Clarence F. Brey, a citizen of the United States, residing at New York city, in the county of New York and State of New York, have invented a new, original, and ornamental Design for a Piano, of which the following is a specification, reference being had to the accompanying drawing, forming part thereof.

The drawing is a perspective view of a piano showing my design.

I claim:

The ornamental design for a piano, as shown.

CLARENCE F. BREY.
